UNITED STATES PATENT OFFICE.

CARL F. BRAUN, OF SAN FRANCISCO, CALIFORNIA.

EVAPORATOR.

1,334,014.

Specification of Letters Patent. Patented Mar. 16, 1920.

Application filed September 4, 1918. Serial No. 252,641.

To all whom it may concern:

Be it known that I, CARL F. BRAUN, a citizen of the United States, residing at the city and county of San Francisco and State of California, have invented new and useful Improvements in Evaporators, of which the following is a specification.

This invention relates to an evaporator, and particularly pertains to an apparatus for producing salt water vapor.

In most common forms of evaporators it has been found that the heating surface could not be uniformly distributed over the disengaging surface with the result that localized priming would occur; that an objectionably large shell is required for accommodating a sufficient heating surface for practical results; and, furthermore, that the coils installed within the shell are usually so formed as to prevent proper draining thereof. With these objections in view it is the object of the present invention to provide an evaporator, the coils of which are simple in construction and may be readily drained and are further arranged within a suitable shell to prevent localized priming and also to permit a compact and conveniently designed apparatus to be produced. It is another object of this invention to provide permanent connections for the induction and eduction pipes upon the shell of the apparatus which will permit the door of the shell and the coils to be removed as a unit without molesting these pipes and allowing their connections with the coils to be automatically broken with the removal of said door.

The present invention contemplates the provision of an evaporator having two main castings, the shell and the door; the door being removable and carrying condensation coils in a manner to establish communication between them and the steam and condensate manifolds when the door is closed.

The invention is illustrated by way of example in the accompanying drawings, in which—

Figure 1 is a view in front elevation illustrating the completely assembled apparatus.

Fig. 2 is a view in side elevation illustrating the device as shown in Fig. 1 and with parts of the shell broken away to more clearly disclose the arrangement of the coils therein.

Fig. 3 is a view in horizontal section illustrating the formation of the shell, the permanent connections for the steam and con-

densate manifolds and the arrangement of the coils in relation to the door of the shell and the manifolds.

Referring more particularly to the drawings, 10 indicates an outer shell forming the body portion of the present structure. This shell is substantially cylindrical in horizontal section having an enlarged lower portion through which a door opening 11 is formed. 60 The upper portion of the shell is reduced and forms a dome. Mounted upon one side of this dome is a relief valve 12, and upon another portion of the dome are suitable gages 13. The top of the dome is formed 65 with a tubular pipe extension 14 at the outer end of which a vertical bolting flange 15 is provided.

Formed integral with the sides of the shell and opposite the door is an inlet passageway 16 and an outlet passageway 17. These passageways are disposed, the former at the upper side of the door and the latter near the lower edge of the door. These passageways extend forwardly and are adapted 70 to register with an inlet manifold 18 and an outlet manifold 19 formed in the body of the removable door 20. These manifold passageways are provided with a plurality of outlets 21, to which the opposite ends of coils 80 22 are fastened. The formation of these coils is particularly shown in Fig. 3, where it will be seen that they have a series of concentric convolutions ending in an eccentric convolution leading to the manifold passageway 19. Further examination of Fig. 1 85 will show that the coils are inclined in a general direction from the top to the bottom of the shell and thus insure that they will properly drain into the manifold, thereby adding 90 95 greatly to the heat transmitting properties of the coils.

The marginal edge of the opening around the door and the shell is formed with an outwardly extending bolting flange 23, which 100 has a plurality of open-ended slots in its edge. This flange corresponds in contour to that of the door, which also has slots adapted to register with those upon the shell flange to receive clamping bolts 24. It is to 105 be noted that there are two perforations shown through the flanges which are not slotted, as indicated at A and B in Fig. 1. These perforations are provided to receive bolts which will temporarily hold the door 110 in place while permitting the other bolts to be fastened within the slots. The lower por-

- tion of the door is provided with two outwardly extending brackets 25 which are spaced from each other and occur near the lower corners of the door. These brackets 5 receive the shanks 26 of roller casters 27 and hold these casters so that the entire weight of the door may rest upon their frames when the door is removed from its bolted position over the opening in the shell.
- 10 An inlet opening 28 is formed near the bottom of the shell and is threaded to receive a sea water pipe 29. This pipe, as shown, extends horizontally beneath the coils 22 and is provided with a number of per- 15 forations through which the water may pass into the shell. The bottom of the shell is also formed with a drain opening 30. It will be understood that the openings 28 and 29 are also provided with bolting flanges to 20 which suitable conduits may be connected. If desired, the shell may be fitted with a salinometer 31, which is particularly shown in Fig. 3.

In operation, the salt water is admitted 25 through the pipe 29 and is allowed to circulate upwardly around the coils 22. These coils receive steam which passes inwardly through the passageway 16 and is then distributed along the manifold 19 and there- 30 after allowed to pass outwardly through the upper ends of all of the coils connected with this manifold. This steam circulates around through the coils and downwardly to the outlets thereof and into the manifold 19. 35 As before stated, the condensed steam will also pass into this manifold. As this manifold extends vertically and has its outlet at the lower end thereof, the steam and condensed liquid will flow outwardly through 40 the passageway 17 and thereafter be carried away through any pipe connection desired.

The heat of the coils will be imparted to 45 the liquid in which they are submerged and this liquid will thereafter be vaporized, said vapor passing off through the dome of the shell and outwardly through the outlet pipe 14. During this operation the relief valve, gages and the salinometer will function in 50 their customary manner to indicate the condition within the shell.

When it is desired to remove the coils for 55 any reason the bolts 24 are removed from their clamping position through the flange of the door and the flange of the shell and thereafter the door is drawn outwardly as it rests upon the casters 27. In order that the casters shall properly register with the floor washers 26' may be interposed between the outer lugs 25 and the shoulders of the 60 caster frames to vary the position of the caster wheels in relation to the shell. As the door is pulled outwardly and is rolled upon the casters the manifolds 18 and 19 will be simultaneously disconnected from the inlet 65 and outlet passageways 16 and 17 and the

coils will be moved bodily without in any way molesting their connections.

The rear sides of the lowermost coils are bound together with an angle plate 32 which has strap hooks 33 engaging the outer coil convolutions. This angle plate has a horizontally extending portion which projects beneath the set of coils and is turned upwardly at its forward end. This portion cooperates with a flat rib 34 formed integral 70 with the bottom of the shell, as particularly shown in Figs. 2 and 3. The forward end of this rib is inclined downwardly and provides a supporting slide for holding up the coils as they are drawn out from the tank or replaced therein. When the coils are to be replaced they are assembled upon the door and are then guided through the opening 11 into the shell. The door will thereafter register with the shell and the communicating passageways from the manifolds will properly register with the passageways 16 and 17. In this position the bolts located at A and B in Fig. 1 may be placed in position and tightened, after which the remaining 80 bolts required to firmly secure the door are applied.

It will thus be seen that the structure here disclosed provides a maximum coil heating surface disposed within a shell of small dimensions, and, furthermore, that the coils may be readily removed without molesting any of the inlet or outlet pipes of the apparatus.

While I have shown the preferred form of 100 my invention as now known to me, I wish it understood that various changes in the construction, combination and arrangement of parts employed may be made by those skilled in the art without departing from the spirit 105 of my invention as claimed.

Having thus described my invention, what I claim and desire to secure by Letters Patent is:

1. In an evaporator having a shell and an 110 opening in the side thereof around which a bolting flange is secured, a door adapted to be bolted to said flange and to close the opening in the shell, a separate steam manifold formed in one side of the door and a condensate manifold formed in the other side of the door and in parallel relation to the steam manifold, and heating coils fixed by their 115 opposite ends to the door and in communication with said manifolds.

2. In an evaporator having a shell and an opening in the side thereof, around which a bolting flange is secured, a door adapted to be bolted to said flange and to close the opening in the shell, separate steam and 125 condensate manifolds formed in the opposite sides thereof as a part of the door, heating coils fixed by their opposite ends to the door and in communication with said manifolds, said coils being horizontally disposed and 130

adapted so that the eduction ends of each coil may be connected to the condensate manifold at a lower level than the induction end thereof, whereby the coils are properly 5 drained.

3. In an evaporator, a heating coil consisting of a pipe forming a series of concentric convolutions one within the other followed by an eccentric convolution whereby 10 by a distribution of the heating surface of the coils will be obtained and the induction opening of the pipe will be disposed at a higher level than the eduction opening, and the entire length of pipe will be inclined in 15 a downwardly direction from the induction to the eduction opening thereof.

4. In an evaporator, a heating coil consisting of a pipe forming a series of concentric convolutions one within the other followed by an eccentric convolution whereby 20 by a distribution of the heating surface of the coils will be obtained and the induction opening of the pipe will be disposed at a higher level than the eduction opening, and the entire length of pipe will be inclined in 25 a downwardly direction from the induction to the eduction opening thereof, a door to which a series of said pipes are secured, and parallel vertical steam and condensate manifolds with which the induction and eduction 30 ends of the pipe are in respective communication.

5. In an evaporator, a heating coil consisting of a pipe forming a series of concentric convolutions one within the other followed by an eccentric convolution whereby 35 a distribution of the heating surface of the coils will be obtained and the induction opening of the pipe will be disposed at a higher level than the eduction opening, and the entire length of pipe will be inclined in 40 a downwardly direction from the induction to the eduction opening thereof, a door to which a series of said pipes are secured, parallel vertical steam and condensate manifolds in the sides of said door with which the induction and eduction ends of the pipe are in respective communication, said steam manifold having an inlet at its upper end, 45 and the condensate manifold having an outlet at its lower end, and permanent passageways upon the shell of the evaporator with which said inlet and outlet passageways may be brought to register when the door is 50 closed.

6. In an evaporator, a heating coil consisting of a pipe forming a series of concentric convolutions, one within the other, followed

by an eccentric convolution, whereby a distribution of the heating surface of said coils 60 will be obtained, and the induction opening of the pipe will be disposed at a higher level than the eduction opening and the entire length of the pipe will be inclined in a downwardly direction from the induction to the 65 eduction opening thereof, and supporting means interposed between each separate coil to hold the same in proper level for draining, a door to which a series of said pipes are secured, parallel vertical steam and condensate manifolds in the sides of said door with which the induction and eduction ends of the pipe are in respective communication, said steam manifold having an inlet at its 70 upper end and the condensate manifold having an outlet at its lower end, and permanent passageways upon the shell of the evaporator upon which said inlet and outlet passageways may be brought to register when the door is closed.

7. In an evaporator having an outer shell with a door opening in the side wall thereof, a door plate adapted to be secured over said opening, a plurality of super-imposed heating coils carried by the door and adapted to be projected into the shell, casters fixed to the door to support the weight thereof when it is removed from the shell, supporting means to hold the outer coil convolutions in spaced relation with one another, said supporting means having a runner, and a flat rib formed on the bottom of the shell upon which said runner is adapted to slide as the coils are drawn into and out of the shell.

8. In an evaporator having an outer shell with a door opening in the side wall thereof, a door plate adapted to be secured over said opening, a plurality of super-imposed heating coils carried by the door and adapted to be projected into the shell, casters fixed to the door to support the weight thereof when it is removed from the shell, supporting means to hold the outer coil convolutions in spaced relation with one another, said supporting means having a runner and a flat rib formed on the bottom of the shell inclined toward the opening of the shell, upon which said runner is adapted to slide as the coils are drawn into and out of the shell.

In testimony whereof I have hereunto set my hand in the presence of two subscribing witnesses.

CARL F. BRAUN.
